UNITED STATES PATENT OFFICE.

FAY O. FARWELL, OF DUBUQUE, IOWA, ASSIGNOR OF ONE-HALF TO THE ADAMS COMPANY, OF DUBUQUE, IOWA.

VARIABLE-SPEED AND REVERSING MECHANISM.

SPECIFICATION forming part of Letters Patent No. 743,156, dated November 3, 1903.

Application filed July 22, 1903. Serial No. 166,619. (No model.)

To all whom it may concern:

Be it known that I, FAY O. FARWELL, a citizen of the United States, residing at Dubuque, county of Dubuque, Iowa, have invented certain new and useful Improvements in Variable-Speed and Reversing Mechanism; and I do hereby declare the following to be a full, clear, and exact description of the invention, such as will enable others skilled in the art to which it appertains to make and use the same.

My invention relates to variable-speed and reversing mechanism, and has for its object to provide a simple and efficient driving mechanism for use in connection with motor-vehicles and other machines in which the power, speed, and direction of rotation of the driven member are subject to frequent change, while the energy and speed of the motor-shaft are maintained practically constant, the changes in speed and direction in the driven member being effected by differential gearing connecting said member with the motor-shaft and with a speed-varying gearing driven from said motor-shaft.

In the accompanying drawings, Figure 1 is a side elevation, partly in section, of a variable-speed and reversing mechanism embodying my improvements. Fig. 2 is a perspective view of the same. Fig. 3 is a transverse section of the casing or frame containing the differential gearing.

Referring to the drawings, *a* represents a driving-shaft, which obviously may be operated from any suitable source of power, as a steam-engine or other motor. Rigidly connected to said shaft is a bevel-gear *b*, above which is a relatively large friction-disk *c*, also mounted upon and revolving with said shaft *a*.

Mounted in suitable brackets or supports *o* and occupying a position at right angles to shaft *a* is a second shaft *h*, hereinafter referred to as the "retarding-shaft." Loosely and revolvably mounted upon said shaft *h* is a sleeve or hollow shaft *e*, upon one end of which is secured a bevel-gear *d*, meshing with and driven by gear *b* on shaft *a*, and upon the other end of said sleeve is a pinion *f*.

Revolvably mounted upon shaft *h* and sleeve *e* and capable of free rotation independently

of said shaft and sleeve is a frame or casing *j*, secured to or forming part of which is a gear or sprocket *k*, from which the power is ultimately taken to drive the motor-vehicle or other machine. Within said frame or casing *j* are mounted planetary gears *m* and *n*, capable of rotation upon supporting studs or pins *l*, supported in the opposite walls of said frame. Gear *n* meshes with pinion *f*, and gear *m* engages a pinion *i* upon shaft *h*, the train of gearing thus provided constituting a differential planetary system by means of which the speed and direction of rotation of frame *j* and power-gear *k* are determined. 65

Spined to shaft *h* and longitudinally adjustable thereon is a friction-wheel *g*, engaging with and driven from disk *c* and serving to impart a variable speed of rotation to said shaft *h*. It is to be understood that suitable 70 lever mechanism is provided for shifting wheel *g* along shaft *h* and for locking said wheel in such shifted position.

Of course it is to be understood that the relative sizes and proportions of the various 75 gears employed will depend upon the circumstances and conditions under which the apparatus is to be operated and must therefore be determined by the designer. In the particular embodiment of the invention illustrated, which is that employed in motor-vehicle practice, gear *b* is one-half the diameter of its mate *d*, friction-disk *c* is more than twice the diameter of friction-wheel *g*, pinion *f* is twice the size of *n* diametrically, and pinion *i* is one-half the diameter of its mating gear *m*. Assuming the speed of shaft *a* to be five hundred revolutions per minute in the direction indicated by the arrow 1, Fig. 1, gear *d*, together with sleeve *e* and pinion *f*, 80 will have a speed of two hundred and fifty revolutions per minute. Now, supposing gear-frame *j* to be held and prevented from rotating and friction-wheel *g* to be out of contact with disk *c*, so that shaft *h* may revolve 85 freely, said shaft will be driven by gear-train *f n m i* in the same direction as gear *d* at four times the speed of said gear *d*, twice the speed of disk *c*, or one thousand revolutions per minute. If wheel *g* be now brought into contact with disk *c* at a point (marked *y*) distant from the center of said disk equal to the

90 95 100

diameter of g , said wheel will revolve shaft h at the same speed that it is normally driven by gear d and the connecting gear-train $f n m i$. If, therefore, frame j be released, it 5 will remain stationary, no motion will be imparted to driving sprocket-gear k , and gears m and n will "idle" on their respective studs. If, however, the wheel g be moved toward the center of the disk c , the point of contact on 10 said disk will move at a slower speed than the normal speed just referred to, and said disk will exert a retarding influence upon wheel g and pinion i , with the result that the speed of rotation of gears m and n will be 15 reduced. Pinion f , however, continues to revolve at the normal speed and will thereby cause the gear-frame j to rotate about shaft h in the same direction as gear d , and planetary gears m and n will continue to rotate 20 about their axis l at a less speed. As the wheel g is moved nearer the center of disk c the latter imparts a greater retarding force to 25 said pinion i and gears m and n , and gear-frame j revolves faster as a whole, while gears m and n rotate more slowly about their axis until a point x is reached, where the driving 30 diameter of disk c is one-half the diameter of wheel g , when said wheel, shaft h , and pinion i travel at the same speed and in the same direction as bevel-gear d , sleeve e , and pinion f . Under these conditions there will be no movement between any of the gears in the gear-frame or casing j or between shaft h , sleeve e , and casing j , and the whole mechanism 35 on shaft h will rotate as a unit with said shaft without friction and without noise. In motor-vehicle practice this relation would preferably be that of highest speed and that most generally employed, as slower speeds 40 on level roads may be secured by regulating the speed of the engine. It will be understood that if a reverse movement of the sprocket k is desired the friction-wheel g is moved farther from the center of disk c than 45 the point marked y , in which event said wheel g and pinion i will rotate at a speed sufficient to reverse the revolution of frame j , and therefore reverse the motion of the driven machine. This reverse motion may 50 be accomplished at any speed desired by enlarging the friction-disk to allow a wide range of movement between point y and the periphery of the disk.

It is to be particularly noted that unlike 55 most friction-drives the friction member does not impart a driving movement, but, on the contrary, merely retards the movement or speed of rotation of the friction-wheel g . As the normal speed of wheel g is four times as 60 great as that of bevel-gear d , it follows that even should there be no friction between shaft h and sleeve e and between the various gears and bearings in the gear-frame the friction-disk would have to impart a retarding 65 effect to the friction-wheel of only one-fourth the power transmitted by bevel-gears b and d . As a matter of fact, however, there is consid-

erable friction between the shaft h , its end bearings $o o$, and the several bearings and gears in the planetary-gear case, and all of 70 this friction tends to retard the speed of shaft h and friction-wheel g , and thus assist disk c in keeping wheel g down to its proper speed to impart motion to sprocket k . It will also be noted that an exceedingly slow and very 75 powerful motion may be transmitted to the sprocket without any material intermediate loss of power, which is unlike the usual friction-drive practice.

The apparatus as described is particularly 80 well adapted to a certain type of horizontally-rotating explosive-engine for motor-vehicles of which I am the inventor; but it is to be understood that the invention is applicable to any class of machines driven from a relatively constant rotating-power source—i. e., a shaft—in which the speed, power, and direction of motion of said machine are susceptible of or require frequent change or variation.

Having thus described my invention, what I claim is—

1. A variable-speed and reversing mechanism, comprising a driving-shaft, a hollow shaft geared thereto, a second shaft upon 95 which said hollow shaft is mounted, a revolute frame on said second shaft, a differential planetary-gear train connecting said frame with the hollow shaft and with said second shaft respectively, a gear from which 100 power is taken connected to said casing, and means operated from said driving-shaft for varying the speed of said second shaft, whereby the frame and power-gear may be driven in either direction and at a variable speed. 105

2. A variable-speed and reversing mechanism, comprising a driving-shaft, a friction-disk and a gear mounted on said shaft, a second shaft, an adjustable friction-wheel mounted on said second shaft and actuated 110 by said friction-disk, a loose sleeve on said second shaft, a gear secured to said sleeve and driven from said first-mentioned gear, a pinion on said sleeve, a differential pinion on said second shaft, a revolute frame having 115 differential gears meshing with the pinions on the sleeve and the second shaft respectively, and a gear from which power is taken connected to said revolute casing, all so proportioned that the speed of the power-gear 120 may be varied or the motion thereof reversed by adjusting the position of said friction-wheel on said second shaft.

3. A variable-speed and reversing mechanism, comprising a driving-shaft, a second shaft 125 at right angles thereto, a bevel-gear and a friction-disk on said driving-shaft, an adjustable friction-wheel on said second shaft driven from the disk aforesaid to rotate the second shaft at variable speeds, a loose sleeve 130 on said second shaft driven by said bevel-gear, a revolute frame from which power is taken on said second shaft and differential planetary gearing connecting said frame with

the second shaft and said sleeve with the frame, whereby the speed and direction of rotation of said frame are controlled.

4. A variable-speed and reversing mechanism, comprising a driving-shaft, a bevel-gear and a friction-disk secured to said driving-shaft, a driven bevel-gear engaging the driving bevel-gear, an adjustable friction-wheel engaging the friction-disk, a planetary differential gearing connecting the driven bevel-gear and the friction-wheel, a supporting-frame for the planetary gear, and means for taking power from the supporting-frame.

5. A variable-speed and reversing mechanism comprising a driving-shaft, a bevel-gear and a friction-disk secured to said driving-shaft, a driven bevel-gear engaging the driving bevel-gear, a spur-gear *f* connected to the driven bevel-gear, an adjustable friction-wheel engaging the friction-disk and revolving in the same direction as the driven bevel-gear, a spur-pinion *i* connected to the friction-wheel of smaller diameter than the spur-gear *f* which is connected to the driven bevel-gear, planetary gearing engaging the pinion

i and the spur-gear *f*, a supporting-frame for the planetary gears and means for taking power from the supporting-frame.

6. A variable-speed and reversing mechanism, comprising a driving-shaft, a positively-driven element revolving at right angles to said shaft, a spur-gear secured to said positively-driven element, a driven gear *i* of smaller diameter than the gear connected to said positively-driven element, a power frame 30 or casing adapted to revolve around the same axis as gears *f* and *i*, planetary gears engaging the gears *f* and *i* secured to the power-casing, a retarding element secured to the driven gear *i*, means for varying the speed 35 of the driven gear *i*, whereby the speed and direction of rotation of the power-frame are controlled.

In testimony whereof I affix my signature in presence of two witnesses.

FAY O. FARWELL.
